UNITED STATES PATENT OFFICE

116,343

DESIGN FOR A MOTOR SUPPORT

William L. Laib, Oak Park, Ill., assignor to Reynolds Electric Company, Chicago, Ill., a corporation of Illinois

Application April 10, 1939, Serial No. 84,181

Term of patent 14 years

To all whom it may concern:

Be it known that I, William L. Laib, a citizen of the United States and residing at Oak Park, in the county of Cook and State of Illinois, have invented a new, original, and ornamental Design for Motor Supports, of which the following is a specification, reference being had to the accompanying drawing, forming part thereof.

In the drawing:

Fig. 1 is a plan view of a motor support, showing my new design;

Fig. 2 is a face view thereof; and

Fig. 3 is a side view thereof.

I claim:

The ornamental design for a motor support, as shown.

WILLIAM L. LAIB.
